UNITED STATES PATENT OFFICE

2,236,294

VENTILATOR

Victor S. Lundell, Jamestown, N. Y.

Application March 1, 1939, Serial No. 259,185

5 Claims. (Cl. 98—96)

This invention relates to an improvement in ventilators and more particularly to ventilators for installation and use with windows of the swinging or sliding type.

5 In the disclosed form, the invention is applied to and forms part of a casement window, being interposed between the glass panel and either the upper or lower window rail. The ventilator engages the window rail and provides a seat and 10 securing for one edge of the glass panel.

One of the objects of the invention lies in the provision of a ventilator for application to a swinging or sliding sash.

Another object of the invention lies in the provision of a ventilator that may be built into a casement sash or subsequently added thereto upon removal of the glass panel and replacement by one of smaller dimensions.

Another object of the invention lies in the provision of a ventilator for a swinging or sliding sash that provides both inside and outside closure means for the ventilator opening.

Another object of the invention lies in the provision of a ventilator having an exterior closure member which serves as a hood or shield to prevent ingress of the elements.

Another object of the invention lies in the provision of a ventilator having an inside closure that serves to prevent foreign particles from 30 entering the space within the ventilator.

Another object of the invention lies in the provision of a ventilator having a closure member adapted to receive and seat a screen.

Other and further objects and advantages of the invention will be more fully understood from a consideration of the following specification taken in conjunction with the accompanying drawing; and in which—

Figure 1 is a perspective view of a casement window in which is embodied one form of the invention;

Figure 2 is a perspective view of the ventilator removed from the casement window illustrated in Figure 1;

45 Figure 3 is a vertical sectional view of the invention, being taken substantially on the line 3—3 of Figure 1;

Figure 4 is a vertical sectional view similar to that of Figure 3, showing the movable element 50 of the ventilator in open position and provided with a screen;

Figure 5 is a fragmentary horizontal sectional view of one end of the ventilator, being taken substantially on the line 5—5 of Figure 3;

55 Figure 6 is a further horizontal sectional view

of one end of the ventilator with the rotatable element removed;

Figure 7 is a vertical sectional view of a modification of the ventilator; and

Figure 8 illustrates the application of the invention to a top position in a window.

Reference is now had to the drawing wherein the numeral 10 is employed to generally designate a conventional casement window structure. The window comprises a frame 11 and sash 12. 10 In cross section the rails of the frame and sash are conventional, as illustrated. In the application of a ventilator, embodying the present invention, to the lower portion of a casement window, said ventilator is designed to rest upon the 15 lower horizontal sash rail 13. This rail includes a horizontal web portion 14, an inner upstanding flange 16, and an outer downwardly directed flange 17. The vertical rails 18 of the sash are similar to the rail 13 in cross section. 20

The ventilator 19 is adapted to be mounted on the rail 13 and comprises relatively fixed and movable members 21 and 22. The fixed member 21, when adapted for use with a casement window, comprises end blocks 23 having vertical 25 channels 24 located adjacent the inner face thereof. These channels are adapted to receive the inwardly projecting flanges of the side rails 18. The blocks 23 are connected by a hood or shield 26. In the present disclosure the hood is 30 formed with slots 27 adapted to receive screws 28 that have threaded engagement with the upper curved surfaces of the blocks. It is apparent, however, that the blocks and hood may be formed integral by stamping from sheet metal or by 35 casting. The outer faces 29 of the blocks 23 are of a generally circular contour, which contour is followed by the hood 26. The inner edge of the hood terminates in an upstanding flange 31 that is in vertical alignment with the channels 40 24 and, therefore, with the inwardly directed flange of the upstanding sash rails 18. The blocks 23, in the present form of the invention, are each formed with a circular bearing portion 45 32 that projects inwardly of the ends of the ventilator and is of a diameter less than the width and height of the blocks.

The rotatable member 22 of the ventilator comprises inner and outer elements 33 and 34. The inner element includes a curved portion 50 36 that terminates in a short flange 37 along one edge and a more extensive flange 38 along the other edge. The curved portion 36 of the element 33 is secured to circular plates 39. These plates are positioned adjacent the ends of the 55

elements 33 and 34, being in close proximity with the bearing portions 32. One or more intermediate plates 39 may be provided, depending on the length of the ventilator. The outer element 5 34 is formed with a curved portion 41 and terminates along one longitudinal edge in an outwardly directed flange 42. The element 34 is secured to plates 39 substantially diametrically opposite the curved portion 36 of element 33. 10 A ventilating passageway 35 is thus provided. The ends of elements 33 and 34, projecting beyond the plates 39, provide partial circular recesses into which the end bearings 32 project. Thus, the member 22 is mounted for rotation in 15 the member 21.

Reference is now had to Figure 7 of the drawing wherein is shown a modification of the structure above described. In this instance, the fixed member 43 includes top and bottom elements 44 20 and 46. The top element is formed with a hood portion 47 similar to the hood 26 heretofore described. However, the upper portion of the hood 47 is made with a horizontal flange 48 that terminates in an upwardly directed flange 49. The 25 lower element 46 is an angular bar having an upstanding flange 51 that terminates in a laterally offset portion 52. The offset portion 52 overlies the upper edge of flange 16 of the rail 13, being in the same vertical plane therewith. The 30 upper and lower elements of this fixed member are connected by end blocks heretofore described. The rotatable member of this modification comprises elements 53 and 54. Element 54 is substantially identical with the element 33 heretofore described. Element 54, however, is formed 35 with an upstanding flange 56 that contacts a shoulder formed at the jointure of the hood 47 with flange 48.

It will be noted in the structure of Figure 3 40 that the rotatable member 22, when in closed position, provides three-surface contact with the fixed member 21; namely, flanges 37, 38, and 42. In the modification of Figure 7, however, due to the additional provision of flange 56, four-surface 45 contact is had between the rotatable member and the fixed member when the ventilator is closed. Furthermore, in the modification, provision of a bottom element 46 may, under certain 50 circumstances, provide better seating for the ventilator on the horizontal window rail 13.

Attention is now directed to Figure 8 wherein is shown an application of the present invention to the top of a casement window. In this instance, the fixed member 57 includes a hood 58 55 that terminates adjacent the downwardly directed flange 59 of the upper horizontal rail 61 of the sash. The lower element of this member is generally T-shaped and includes upper and lower flanges 62 and 63. The upper flange serves 60 as a stop to limit movement of the rotatable member and the lower flange substitutes for flange 59 in the positioning of a glass panel 64. The rotatable member 66 may be substantially 65 identical with the rotatable members heretofore described.

It is to be particularly noted in the present invention that the rotatable member is comprised of two semi-circular spaced apart elements and that the flanges on these elements serve as stops 70 to limit movement and to constitute a contact seal when the ventilator is closed. Furthermore, the ventilator is closed exteriorly as well as interiorly by the provision of two rotatable elements. Thus, neither dirt, nor snow, nor ice 75 can interfere with the proper functioning of the

device. In Figure 4 of the drawing there is shown a section of screening 61. Should it be found necessary to screen a ventilator of this type, a small piece of screening may be cut and inserted into the circular portion of the rotatable member in a curved position and the natural springiness of the screen will hold it in place. It is to be understood that the inner and outer elements of the rotatable member are substantially in balance and, therefore, no spring or latch means is required to maintain the ventilator in either open or closed position. Furthermore, should the ventilator be open and a storm occur, it is conceivable that wind striking the large flange 42 would close the ventilator. 15

The present invention, as mentioned above, is adaptable for mounting in windows previously installed. The procedure simply involves removing the glass panel, inserting the ventilator in the sash frame, shortening the glass equivalent 20 to the ventilator height, and repositioning said glass.

Although applicant has shown and described only a few of several modifications of the invention and its application to a casement window, 25 it will be understood by those skilled in the art that other modifications or variations of the structure may be made and are contemplated insofar as they are within the spirit and scope of the invention as defined in the hereunto annexed claims.

Having thus set forth my invention what I claim as new and for which I desire protection by Letters Patent is:

1. In a window structure having a frame and panel, a ventilator comprising a frame engaging member, said member cooperating with said frame to bound said panel and having a ventilating opening therein, a rotatable member mounted in said opening, the ends of said rotatable member being recessed and receiving corresponding portions of the frame engaging member to provide relative pivotal movement of the members, said rotatable member including spaced elements adapted, when said ventilator is closed, 45 to provide inner and outer closures for said opening.

2. In a window structure having a frame and panel, a ventilator interposed between one end of said panel and an adjacent rail of said frame, 50 said ventilator comprising fixed and rotatable members, said fixed member being engaged with said window frame and cooperating therewith to provide a ventilating opening, a portion of said fixed member projecting laterally beyond 55 said window as a hood for said opening and means pivotally supporting said rotatable member in said opening.

3. In a window structure having a frame and panel, a ventilator comprising a stationary member, means forming a part of said member engageable with certain of the rails of said frame, a portion of said member projecting laterally beyond the vertical confines of said window to form a hood, said member having a rectangular ventilating opening, a rotatable member mounted for pivotal movement in said opening, and means on said rotatable member, said means, when said ventilator is closed, serving as an exterior closure adjacent said hood. 70

4. In a window structure having a frame and panel, a ventilator comprising a stationary member interposed between one edge of said panel and an adjacent rail of said frame, said member having a rectangular transverse ventilating open- 75

- ing, a hood on said member projecting laterally beyond the vertical confines of said window and partially closing the exterior end of said opening, a rotatable member mounted for pivotal movement within said opening, and means on said rotatable member cooperating with said hood to close the exterior end of said opening when said ventilator is closed.
5. In a window structure having a frame and panel, a ventilator comprising a stationary member interposed between one edge of said panel and an adjacent rail of said frame, said member
- 10

having a rectangular transverse ventilating opening, a hood on said member projecting laterally beyond the vertical confines of said window, a rotatable member mounted for pivotal movement in said opening, spaced elements forming part of said rotatable member, said elements, when said ventilator is in closed position, serving as closures for the interior and exterior ends of said opening and being in contact with said member and said frame.
